TRAIN LINE COUPLING

Raymond John Travers, Youngstown, Ohio

Application December 21, 1948, Serial No. 66,543

2 Claims. (Cl. 285—162)

1

This invention relates to railroad equipment and more particularly to train line couplings for rolling stock.

The principal object of the invention is the provision of a movable, yieldable train line coupling.

A further object of the invention is the provision of a train line coupling capable of transverse and longitudinal movement to avoid breakage by accidental engagement of train couplers therewith.

A still further object of the invention is the provision of a simple and inexpensive train line coupling providing telescopic action between the train line and the portion thereof extending beyond the end sill of the railroad car.

A still further object of the invention is the provision of a flexible movable train line coupling providing an air-tight train line connection in normal operation.

The train line coupling shown and described herein comprises a simple and efficient mechanism for establishing communication of the train line between adjacent railroad cars and providing at the same time a structure which will not be damaged in the event it is accidentally struck or moved by the railroad car couplers. It is well known that frequent and costly damage occurs to the train line couplings when railroad cars and particularly freight cars are switched about in a freight yard and the cars recoupled as in making up a train. The damage occurs primarily by reason of the couplers on the cars being out of alignment and striking the train line couplings, thereby bending, breaking or otherwise damaging either the train line couplings themselves or the flexible hoses connected thereto. Such delays and interruptions as have heretofore been occasioned by such accidental breakage are eliminated completely by the use of the train line couplings disclosed herein.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The invention is illustrated in the accompanying drawing, wherein—

Figure 1 is a side view of portions of railroad cars having sections broken away and illustrating the train line couplings.

2

Figure 2 is a top plan view taken on line 2—2 of Figure 1.

Figure 3 is a horizontal cross section taken on line 3—3 of Figure 1 on an enlarged scale.

By referring to the drawings and Figures 1 and 2 in particular it will be seen that adjacent end portions of a pair of railroad cars 10 and 11 are illustrated and each of which is provided with the conventional couplers 12 and 13, respectively. The end sills of the cars are indicated by the numerals 14 and 15 and the train line in each of the cars is indicated by the numerals 16 and 17, respectively. As is well known, the train lines provide means for conveying compressed air through the various cars of the train for actuation of the air brakes.

In Figure 1 of the drawings the couplers 12 and 13 are shown in uncoupled relationship and the train lines 16 and 17 are shown equipped with train line couplers 18 and 19 which include telescopic sections 20 and 21, respectively. The telescopically engaged sections 20 and 21 extend through the end sills 14 and 15, respectively, as heretofore described, and are normally biased 25 toward one end of a slot-like opening therein by means hereinafter disclosed. Both of the train line couplings 18 and 19 comprise essentially elongated cylindrical members as best shown in Figure 3 of the drawings wherein the coupling 18 is shown in enlarged detail. The coupling 18 is connected directly with the train line 16 and is provided with a removable cap 22 on the opposite end thereof, the cap forming a gland 23 about the telescopically engaged portion 20 of the coupling 18.

The inner end of the telescopically engaged portion 20 is provided with a flange 24 which is preferably secured thereto as by welding. A resilient gasket 25 is disposed between the inner side of the cap 22 and the flange 24 so that an air-tight connection is made between the cylindrical member of the coupling 18 and the telescopically engaged portion 20 thereof when the flange 24 is in registry therewith. A coil spring 26 is disposed within the cylindrical body of the train line coupling 18 and engages the flange 24 and the opposite end of the coupling member and normally holds the flange 24 in engagement with the gasket 25. It will be obvious to those skilled in the art that the cylindrical body of the coupling 18 may be connected with the train line 16 by way of a cap comprising a duplicate of the cap 22 heretofore referred to in place of the upset end construction illustrated. The telescopically engaged portion 20 of the device extends through

the end sill 14 by way of an elongated slot located therein, oppositely disposed face plates 27-27 being positioned one on each side of the end sill 14 and serving to cage a secondary coil spring 28. A U-shaped bracket 29 is positioned between one end of the secondary coil spring 28 and the telescopically engaged portion 20 of the coupling and tends to hold the device in one end of the slot in the end sill 14 as shown. It will be obvious that the train line coupling is held in position away from the car couplers 12 and 13 heretofore referred to.

By again referring to Figures 1 and 2 of the drawings it will be seen that the outermost end of the telescopically engaged portion of the coupling 18 is provided with an angle cock 30 to which a section of flexible hose 31 is secured which is provided with a conventional coupler 32 on its outermost end. The entire train line coupling is suspended in the railroad car by suitable means such as hangers 33 which provide the transverse motion necessary and, additionally, support the train line couplings against end thrust. In operation, it will be seen that the accidental engagement of either of the main couplers 12 or 13 against the train line couplings will result in their sideward movement and, most importantly, their longitudinal movement with respect to the railroad car on which they are installed, thus avoiding breakage or damage which would otherwise necessitate laying up the car for repairs.

It will further be seen by those skilled in the art that the train line coupling disclosed herein may be economically fabricated as it comprises essentially sections of tubular members and that it may be installed easily and economically in existing rolling stock by simply coupling the same to the train lines at a point in back of the end sills of the cars.

It will thus be seen that a simple and efficient train line coupling has been disclosed which meets the several objects of the invention.

Having thus described my invention, what I claim is:

1. A train line coupling comprising an elongated cylindrical member in communication at one end with said train line, a tubular member having an outturned flange formed on one end thereof and telescopically engaged in said cylindrical member, with the said outturned flange positioned therein, a cap on said cylindrical member guiding the said tubular member, a gasket

disposed within the said cap and for engagement with the said flange to form an air seal between the cylindrical member and the tubular member when they are in maximum extended relation, a coil spring within the said cylindrical member and positioned between the same and the said flange so as to urge the flange against the said gasket, the outermost end of the said tubular member extending outwardly and having an angle cock and a section of flexible hose secured thereto, the device acting to absorb endwise motion imparted thereto as by the coupler of an adjacent railway car.

2. A train line coupling comprising a cylindrical body member having an inlet opening at one end in communication with the train line and an apertured cap on the other end, a tubular body member the diameter of which is less than the inner diameter of the said cylindrical member and reciprocally positioned through said apertured cap, an outturned flange formed on the inner end of the said tubular member and slidably engaging the inner surface of the said cylindrical member, a spring positioned between the inlet end of the said cylindrical member and the said flanged end of the said tubular member and a gasket positioned within the said capped end of the said cylindrical member through which the said tubular member extends and forming with the said flange, an air seal, the said spring normally urging the said flanged tubular member against the said gasket to prevent the leakage of air through the said train line coupling, the other end of the said tubular member extending outwardly from the said apertured cap and provided with an angle cock and a section of flexible hose secured thereto, the device acting to absorb endwise motion imparted thereto.

RAYMOND JOHN TRAVERS.
